UNITED STATES PATENT OFFICE

108,485

DESIGN FOR A COMBINATION MIRROR, LIP-STICK, AND POWDER HOLDER

Sadye Elaine Wallace, New York, N. Y.

Application July 28, 1936, Serial No. 64,092

Term of patent 3½ years

To all whom it may concern:

Be it known that I, Sadye Elaine Wallace, a citizen of the United States, residing at New York, in the county of New York and State of New York, have invented a new, original, and ornamental Design for a Combination Mirror, Lipstick, and Powder Holder, of which the following is a specification, reference being made to the accompanying drawing, forming part thereof.

The figure is a perspective view of a combination mirror, lipstick, and powder holder, showing my new design.

I claim:

The ornamental design for a combination mirror, lipstick, and powder holder.

SADYE ELAINE WALLACE.
